United States Patent Office.

J. Y. SMITH, OF PITTSBURG, PENNSYLVANIA.

Letters Patent No. 64,043, dated April 23, 1867.

IMPROVEMENT IN STEAM-ENGINE PISTONS.

The Schedule referred to in these Letters Patent and making part of the same.

TO ALL WHOM IT MAY CONCERN:

Be it known that I, J. Y. SMITH, of Pittsburg, in the county of Allegheny, and State of Pennsylvania, have invented certain new and useful improvements in Metal Packings for Pistons in Engines; and I do hereby declare that the following is a clear, full, and exact description thereof, reference being had to the accompanying drawings, making part of this specification, and to the letters of reference marked thereon, like letters indicating like parts wherever they occur.

Figure 1 is a side view; and

Figure 2 is a longitudinal section.

My invention relates to that style of packing in which metallic rings are used, and where the steam itself acts upon the rings to cause them to pack the piston in the cylinder; and it consists in a novel construction of the rings, and of their arrangement in connection with the piston-head.

To enable those skilled in the art to construct and use my invention, I will proceed to describe it.

I first construct a piston-head, consisting of the central core A and the radial flanges A', these latter being separated by the circumferential groove or channel α , as represented in the drawings. It will be observed that this channel or groove α is made with its sides inclined, as shown in fig. 2, thereby making the channel wider at its bottom than at its outer point. I then construct a metal ring, c, which is made wider at its base inside than on its outside, and also a ring, e, having its outer surface wider than its inner surface, the adjoining sides of said rings being bevelled or inclined at a corresponding angle, so that when slipped on the core A their inclined sides shall fit snugly together, as represented in fig. 1. These rings are cut through, as represented by the dotted line i of fig. 1, so as to permit them to yield to the pressure under them, and thus to expand and increase in diameter, to fill and pack the space between the piston-head and the cylinder. If desired, these joints i in the packing rings may be covered by a piece, t, as represented in fig. 1, this piece being fitted into a suitable recess formed on the side, and also on the outer or inner surface of the rings, as may be preferred. The rings c and e are made of such a size as to fit loosely upon the core A, and leave a space between their inner surfaces and the core, as shown in fig. 2. They are held on the core by the end-plates B, and are made of such a thickness as to just fill, loosely, the space between the inner walls of the plates B and the flanges A'. A series of holes, n, are made through the flanges A', as represented in fig. 2, so as to communicate between the central groove α and the space under the packing rings c and e, the arrangement of rings and the flange and plate being duplicated on each side of the central groove α , as shown in both figs. 1 and 2. The parts being thus arranged, are attached to the piston-rod C, and, altogether, constitute the piston-head and packing, and is then inserted into the cylinder in the usual manner.

In operation, the steam which may pass by the rings on one end will enter the groove α , and passing through the holes n will press against the inner surface of the rings, thereby distending them and causing them to pack so tightly as to prevent the leakage of any steam past the head in the cylinder. As the ring c presents more surface for the action of the steam than e does, it will be expanded more than e, and on account of their inclined sides, will act as a wedge to force the rings outward against the walls of the flange A' and plate B, thus packing between them so as to prevent the escape of any steam from underneath the rings. So, also, as the rings are expanded by heat, the ring c having more metal to be acted upon on its inner surface than e, will thereby be more expanded, and consequently operate in the manner above described.

The groove α may be purposely filled with water, or it may become so filled by the condensation of the steam, and still the operation of the parts will be the same, as it is obvious that any steam pressing on the water or other fluid in the groove α will force it through the holes n into the space under the rings, and will press them outward just in proportion to the pressure applied, and thus by a very simple construction of parts I am enabled to produce a packing for pistons that is cheap, durable, and efficient. It is obvious that the steam which escapes past the rings into the central groove α will become condensed therein more or less, and that thus after a little time the groove will become more or less filled with water, which will serve not only to pack or press the rings, instead of steam, but it will also serve as a lubricant for the piston. By inserting a cock in the side of the cylinder at any proper point, and moving the piston so as to bring the groove α opposite the inner end of the cock or tube, oil or any other suitable lubricating material may be inserted into said groove for the purpose

of lubricating said piston; and thus I am enabled to accomplish the twofold purpose of packing and lubricating the piston at the same time.

Having thus described my invention, what I claim, is—

1. The central groove *a*, provided with the apertures *n*, for admitting the steam or other material to the under side of the rings, substantially as shown and described.
2. The combination of the rings *c* and *e* with the flanges *A'* and plate *B*, or their equivalents, when arranged and operating as and for the purpose set forth.

J. Y. SMITH.
